MARINE ANCHOR

Carlton W. Filby, Jefferson, Ohio

Application October 8, 1938, Serial No. 233,968

2 Claims. (Cl. 114—207)

My invention relates to improvements in marine anchors and grapples and has for advantages, reduced weight and bulk, better holding qualities, less cumbersomeness and lower cost of production.

To attain these ends there is provided a bar curved at one end to form a hook at such an angle as to insure the best grapping qualities. Attached to this hook is a pointed plate or fluke designed to engage in or grip the sea bed. The reverse end of the bar is provided with a swivel for attaching a cable.

To maintain the anchor in the best operating position a submersible float attached to a lever arm is provided. Said lever arm is pivoted to the previously mentioned hooked bar and secured by means of a bolt and wing nut in such manner as to allow the float to be folded down against the main bar for convenience in stowing and handling.

The annexed drawing is an elevational view of said anchor. Figure 1 is a perspective view showing the anchor in operating position. Figure 2 is a similar view showing the anchor folded for stowing.

My anchor is formed with the usual straight bar portion, or shank, 1. An end of this shank is turned back upon itself to form a hook 1' to which is attached a fluke, or palm 2, having any desired proportions adapting it for penetration of sea bottom and holding. The other end of shank 1 is provided with a swivel 3 to which a vessel cable or hawser will be attached in use.

For the purpose hereinbelow stated a float 4 is provided. This float 4 is mounted on the free end of a lever arm 5 which is pivotally attached

to the shank 1 near the curved portion, or hook 1', carrying the fluke 2. This arm 5 is so mounted that it extends from the shank in a direction opposite the direction in which the fluke-bearing bent portion 1' of the shank extends. That the arm and float may be securely retained in a folded position, when stored, a wing-nut 6 is provided for the bolt upon which the arm 5 pivots.

In use, the anchor is lowered with the arm 5 carrying the float 4 normal to the shank 1 as is shown in Figure 1. The anchor sinks, overcoming the supporting buoyancy of the float, and presents the fluke, or palm, to the sea bottom in the correct position for penetration.

The employment of a float eliminates the necessity of providing additional flukes, or a stock or arm for maintaining the anchor in an operating position.

I, therefore, point out and distinctly claim as my invention:

1. An anchor comprising a shank, palm, float and means pivotally connecting said float to said shank near said palm, the length of said means being no greater than the length of the shank, whereby the float will normally be submerged when in use.

2. An anchor comprising a shank, fluke, float, and a rigid arm attached to said shank near the fluke, which arm has said float mounted on its free end, said arm having a length such that said float will be submerged when the anchor sinks in use, and by its buoyancy will maintain the anchor with said fluke in a position to enter the sea bottom.
